CLAIM

The ornamental design for a multiple game portable storage container, as shown and described.

DESCRIPTION

FIG. 1 is a front elevational view of the multiple game portable storage container showing our new design; FIG. 2 is a rear elevational view thereof;

FIG. 3 is a right side view thereof;

FIG. 4 is a left side view thereof;

FIG. 5 is a top plan view thereof; and

FIG. 6 is a bottom plan view thereof;

FIG. 7 is an isometric view thereof, wherein the cover is open and the upper interior tray has been dislodged;

FIG. 8 is an isometric view thereof, wherein the cover is open and all of the interior trays have been dislodged; and, FIG. 9 is a fragmentary isometric view of the underside of the upper tray, depicting the grooves which interlink with the lower trays.
